UNITED STATES PATENT OFFICE.

FREDERICK R. SEIDENSTICKER, OF WEST MERIDEN, CONNECTICUT,
ASSIGNOR TO BRADLEY & HUBBARD, OF SAME PLACE.

DESIGN FOR CHANDELIER.

Specification forming part of Design No. **8,042**, dated February 2, 1875; application filed June 3, 1874.
[Term of Patent 7 years.]

CASE C.

To all whom it may concern:

Be it known that I, FREDERICK R. SEIDENSTICKER, of West Meriden, in the county of New Haven and State of Connecticut, have invented a new Design for Chandelier; and I do hereby declare the following, when taken in connection with the accompanying illustration and the letters of reference marked thereon, to be a full, clear, and exact description of the same, and which said illustration constitutes a part of this specification, and represents a perspective view.

This invention relates to a design for chandelier, and consists, first, in the form of an ornament on the spindle above the arms; second, in the configuration of the arms.

The ornament consists of a spherical-shaped center, *a*, around which is a band from which project radial honeysuckle ornaments *d*, and from these, up and down, a winged-shaped honeysuckle ornament, *e*, as shown.

The arms consist of a horizontal bar, *f*, projecting radially from the body. From the end of this bar the arm *g* curves downward and outward, terminating in a horizontal rest, *h*, for the lamp or burner. Above the bar *f* the arm extends upward, *g'*, and, turning at right angles, *i*, returns, *l*, to the bar, and below turns, *n*, onto the main arm, as shown.

I claim as my invention—

1. The design for chandelier-spindle ornament, consisting of the spherical body *a* and radial ornament *d*, with combined vertical ornaments *e*, as shown.

2. The design for chandelier-arm, consisting of the radial horizontal bar *f*, with the arm *g* *h* *i* *l* *n* running up and down therefrom, and of the form shown and described.

FREDERICK R. SEIDENSTICKER.
